UNITED STATES PATENT OFFICE

1,998,259

ABRADING DEVICE

Arthur S. Sorensen, Omaha, Nebr.

Application September 17, 1932, Serial No. 633,550

4 Claims. (Cl. 51—213)

This invention relates to abrading devices and is an improvement on the co-pending applications of Jake M. Stivers, Serial No. 508,965, filed January 15, 1931, and Serial No. 623,881, filed July 21, 1932.

One of the objects of my invention is to provide improved means for holding any one of the three stones desired in horizontal position during use.

Another object is to provide an improved construction of rotor or holder for supporting the sharpening stones.

Still a further object is to provide improved means for rotatably mounting the rotor in a receptacle containing oil, with means for tightening 15 the rotor against rotation and yet permitting loosening of the same sufficient to permit rotation of the rotor when it is desired to either place another one of the stones in uppermost horizontal position or move the stones through the oil in the receptacle to wash from the operating face of the 20 stone any accumulated bits of metal, dirt or other material that would interfere with the efficiency of the stone.

As is well known, the sharpening of cutting blades on rotating grinders tends to remove the temper from such blades, hence such method of sharpening blades is not looked upon with favor by those having blades to sharpen. Butchers and others requiring constant use of 25 cutting blades prefer the old manner of whetting a knife or the like to sharpen the same, but such method consumes considerable time, and is rendered more difficult by the accumulation of grease or other foreign particles on the face of 30 the stones that tend to fill up the pores of the stone and cause the face of the latter to become glazed over, and of such degree of slickness as to very greatly impair its sharpening efficiency.

My improved apparatus, in common with the 40 Stivers applications referred to above, contemplates the mounting of a plurality of sharpening stones upon a rotor, which rotor is rotatably mounted in a receptacle of such nature that it will hold, without leaking, a quantity of oil in 45 which the stones will be immersed as they are rotated, and in addition to being kept in good sharpening condition, will be kept free from grease and other foreign particles that would impair their efficiency. As pointed out in the 50 Stivers application, Serial No. 623,881, the stones are swung in space except for the oil in the receptacle, which oil should be of a penetrating nature such that it will penetrate the pores of the stone and function effectively in washing any 55 foreign particles from the surface of the stone.

My improvements over the said Stivers applications will become more readily apparent from the following specification.

Other objects, advantages and capabilities will later more fully appear.

My invention further resides in the combination, construction and arrangement of parts illustrated in the accompanying drawings, and while I have shown therein a preferred embodiment, I wish it understood that the same is susceptible of modification and change without departing from the spirit of my invention.

In the drawings:

Figure 1 is a side elevation of the receptacle in which the rotor and stones are mounted with the cover in place, a portion of the right-hand side of the receptacle being broken away to show the rotor and stones mounted therein.

Fig. 2 is a perspective view of the receptacle with the cover removed and with one of the stones 20 fastened in horizontal position ready for use.

Fig. 3 is a perspective view of the rotor with the stones mounted thereon.

Fig. 4 is a perspective view of the rotor with the stones removed.

Fig. 5 is a perspective view of one of the sharpening stones with a sheet of cardboard or the like referred to later, slightly removed from the bottom face and showing the clamping plate slightly removed from one end.

Fig. 6 is a vertical longitudinal section with the cover shown in dotted lines.

Fig. 7 is a vertical transverse section taken on the line 7—7 of Fig. 6 and looking in the direction of the arrows.

Fig. 8 is a vertical transverse section taken on the line 8—8 of Fig. 6 looking in the direction of the arrows.

Referring in detail to the drawings, the rotor or holder upon which my abrading stones are carried is rotatably mounted in the receptacle 1, upon which is removably positioned the cover 2 for preventing entry of dust, dirt and the like into the oil in the receptacle, when the device is not in use.

Spot welded or otherwise fixed in the ends of the receptacle (one in each end) are the metal plates 3 and 4, the upper edges 5 of each of these plates being slightly bent inwardly toward the rotor to form a clamping edge on its inner face, 45 which cooperates with and engages over any one of the shoulders 6 of plate 1, which is spot welded or otherwise fixed to the end plate 18 of the rotor just inside and closely adjacent the metal plate 3. As seen in Figs. 2 and 6, plates 3 and 4 are 55

provided with slots 9 and 10, which receive the reduced portions 11 and 12 of the trunnions securely fixed, one at each end of the rotor 13.

The trunnion carrying the reduced portion 12 is secured to the end wall 15 of the rotor 13 by riveting the head 14 to the adjacent portions of the end plate 15, there being a hole provided through said end plate through which the reduced portion 16 may be passed prior to the riveting of head 14. This may be also further secured by spot welding if desired. Just outside of the reduced portion 12 is an enlarged portion 17, which carries the enlarged knurled rotating handle grip 31 referred to later herein (see Fig. 6). The other end wall 18 of the rotor has an opening through which passes the reduced portion 19, after which the head 20 is riveted into place. Just outside of the opening through which the reduced portion 19 passes is a flange 20a to prevent movement of the trunnion 11 into the rotor. Trunnion 11 as shown in Fig. 6 is screw threaded to receive the nut portion 21, which upon rotation in the proper direction, causes the flange 5 to be tightly held to overhang the adjacent shoulder 6 to hold the rotor against rotation. As seen in Fig. 3, there being provided three stones, there will also be provided a like number of shoulders 6 extending parallel to the top face of the adjacent stone, and whichever one of these shoulders 6 is uppermost will be the one in clamping engagement with the flange 5. As will be readily understood, the tightening of nut 21 will draw the rotor longitudinally to the left in Fig. 6 to bring about the locking engagement between flange 5 and shoulder 6.

When it is desired to rotate the rotor to bring one of the other stones uppermost, all that is necessary is to loosen nut 21 a sufficient distance to free shoulder 6 from flange 5, and then turn the rotor to bring the desired stone into uppermost horizontal position.

As will be seen from what has gone before, the opposite end of the rotor is supported in slot 10 by the reduced portion 12 of the trunnion at that end of the rotor. This reduced portion 12 is of sufficient length to permit a reasonable amount of longitudinal movement of the rotor in receptacle 1 to permit tightening and loosening of the rotor by nut 21. When it is desired to remove the rotor from the receptacle, all that is necessary is to loosen nut 21 a sufficient amount and lift the rotor out of the receptacle.

The construction of the rotor will now be described. Extending between the end walls 15 and 18 in the rotor and spot welded or otherwise secured thereto are the metal plates 22, each provided at each end with flanges 23 and 24, and upon which flanges and the end walls the spot welding or other securing means is applied. Prior to fastening these plates 22 in position between the end walls, the trunnions are properly secured in place in the end wall members. When the plates 22 are secured to the end walls as just pointed out, this will provide a rotor of triangular shape having a trunnion at each end to be inserted in the slots 9 and 10. The abrading stones 25 are then laid in place on the plates 22, the stones being of such length to just neatly fit within the flanges 23 and 24, with sufficient room between the end of the stone and flange 24 to slidably receive the metal strip 26. Prior to placing the stone 25 on plate 22, a strip of cardboard or other porous material 27 is applied to plate 22 to lie between said plate and the stone, in order that the penetrating oil in receptacle 1

may penetrate through the cardboard or other porous material, and thus more readily find its way to the under face of the stone to saturate the stone with oil.

As seen in Fig. 6, a suitable opening is drilled through end plate 15 and flange 24 and provided with threads to receive the set screw 28, on rotation of which set screw the stone will be clamped between the metal plate 26 and flange 23 of plate 22. Each of the other stones is fastened to its respective plate 22 of the rotor in a similar manner. Each of the other plates 22 are also secured to the end walls 15 and 18 of the rotor in a manner similar to that described above.

Receptacle 1 has oil placed therein to a suitable height, as for example to come to the level indicated by the line 30, or more or less as desired, the amount of oil being such as to keep the stones saturated and to wash off any foreign particles from the cutting face of the stone as the stones are moved through the oil by rotation of the rotor.

It is also to be noted that when nut 21 is loosened, the knurled cylindrical portion 31 on the right hand end of Figs. 6 and 7 may be used for rotating the rotor to bring the desired stone into uppermost position for use.

It is also understood that the sharpening stones will be of varying fineness, as for example, one being rather coarse for the first sharpening operation, the second one somewhat finer for a medium operation, and the third one of sufficient fineness to finish the sharpening operation. In use the operator will draw the blade to be sharpened back and forth over the faces of the stone until the desired sharpness is attained.

Having now described my invention, I claim:

1. In an abrading device comprising abrading elements and a support therefor, a rotatable holder for said elements comprising a pair of spaced end plates and three side plates each provided at each end with a flange, each of said flanges being secured to one of said end plates with the side plates triangularly arranged to present three faces with an upstanding flange at 40 each end.

2. In an abrading device comprising abrading elements and a support therefor, a holder for said elements comprising a pair of spaced end plates and side plates connecting said end plates and for supporting said abrading elements, upstanding flanges at each end of the holder and each flange secured to one of said end plates with the side plates arranged to present three faces with an upstanding flange at each end, 55 said abrading elements seating against said side plates and secured between said upstanding flanges.

3. In an abrading device comprising abrading elements, a receptacle for containing oil for lubricating said elements, a holder for carrying said elements and including a pair of spaced end plates, three side plates each provided at each end with a flange, each of said flanges being secured to one of said end plates with the side plates triangularly arranged to present three faces with an upstanding flange at each end, a trunnion secured in each of the end plates to furnish journals for mounting the holder in the support, an abrading element secured between the end flanges of each of said side plates, and locking means for retaining the holder against rotation in the receptacle, said locking means including a plate adjacent one of said end plates and means on the receptacle against 70 75

which an edge of said plate contacts for retaining the holder in an adjusted position.

4. In an abrading device comprising abrading elements, a receptacle for containing oil for lubricating said elements, a holder for carrying said elements and including spaced end plates, members connecting said end plates and adapted to support said abrading elements at an angle to one another, upstanding projections on each end plate and the connecting members arranged 5 to present three faces with one of said upstanding projections at each end thereof, a trunnion

projecting from each end plate, an abrading element secured between the upstanding projections on said end plates and seating upon said connecting members, and means for retaining said holder in a predetermined position, said means comprising a triangular-shaped member adjacent an end plate and adapted to engage a projecting portion of said receptacle whereby said projecting portion will prevent rotation of said holder.

5

ARTHUR S. SORENSEN. 10
